UNITED STATES PATENT OFFICE.

WILLIAM C. ANDERSON, OF LANSING, MICHIGAN, ASSIGNOR TO AMERICAN CUT GLASS COMPANY, OF LANSING, MICHIGAN, A CORPORATION OF MICHIGAN.

DESIGN FOR A CUT-GLASS VESSEL OR SIMILAR ARTICLE.

41,413.

Specification for Design.

Patented May 30, 1911.

Application filed December 10, 1910. Serial No. 596,739. Term of patent 7 years.

To all whom it may concern:

Be it known that I, WILLIAM C. ANDERSON, a citizen of the United States of America, residing at Lansing, in the county of Ingham and State of Michigan, have invented a certain new, original, and ornamental Design for Cut-Glass Vessels or Similar Articles, of which the following is a specification, reference being had therein to the accompanying drawings, forming part thereof, in which—

Figure 1 is a plan view of a glass vessel, showing my new design, and Fig. 2 is a side elevation thereof.

I claim:

The ornamental design for a cut glass vessel or similar article as shown.

WILLIAM C. ANDERSON.

Witnesses:

M. F. CHAFEE,
MINNIE FELZKE.
